The ornamental design for a cabinet panel and handle, as shown and described.

DESCRIPTION

FIG. 1 is a top front perspective view of a cabinet panel and handle showing my new design;

FIG. 2 is a reduced front elevational view thereof;

FIG. 3 is a reduced top plan view thereof;

FIG. 4 is a reduced left side elevational view thereof, the right side being a mirror image of the left side;

FIG. 5 is an enlarged fragmentary sectional view taken in the direction of the arrows on line 5—5 of FIG. 2;

FIG. 6 is an enlarged fragmentary sectional view taken in the direction of the arrows on line 6—6 of FIG. 2;

FIG. 7 is a reduced bottom plan view thereof; and

FIG. 8 is a reduced rear elevational view thereof.

The fragmentary broken line representation of a cabinet top and housing in FIGS. 1—4 and 7—8 is for purposes of illustration only and forms no part of the claimed design.
